Des. 187,105
Patented Jan. 26, 1960

187,105

LAMP

Fred Bering, New York, N.Y.

Application February 26, 1958, Serial No. 49,797

Term of patent 14 years

(Cl. D48—20)

I claim:

The ornamental design for a lamp, substantially as shown.
